**METHOD OF MOUNTING PIVOTED LATCHES ON
SELF-ACTING NEEDLES FOR KNITTING AND
RELOOPING MACHINES**

Marcel Vitoux, Troyes, France

Application September 21, 1950, Serial No. 185,914

1 Claim. (Cl. 163—5)

This invention relates to needles of the kind used for performing knitting and relooping works either by hand or by means of machines, in which the catch or beak is closed by a rocking latch mounted for pivotal motion in a suitable slit or groove formed in the body or stem of the needle.

It is known that in needles of this type, the latch is mounted, as a rule, for pivotal motion, on a tiny metal pin having its ends retained through screw means or riveted in upturned side portions of the needle body on either sides of the latch.

It is generally admitted that this method of mounting latches for pivotal motion in latch-needles offers serious drawbacks. Thus, the assembling of such tiny parts is most difficult as the tapping, thread-cutting and riveting steps are delicate operations whereby detrimental inaccuracies and a high percentage of rejections are frequently experienced; furthermore, when the pin ends have been riveted in the aforesaid side portions of the needle body and the thus formed assembly hardened, it is impossible to remove the latch for replacement, a still further trouble resulting from this conventional mounting being the fact that the thread is sometimes caught by the riveted ends of the pivot pin.

Moreover, metallic pins are a drawback in themselves as they wear out quite rapidly if badly lubricated, while correct lubrication of these members is frequently made impossible when knitting white, or clear coloured fabrics, this wear being always considerable owing to the metal-to-metal friction produced.

The object of this invention is to avoid these various drawbacks and it is based on the principle of utilizing the properties of certain synthetic plastic materials which can be deformed temporarily when compression or pulling forces are applied thereto, with or without the assistance of heat, and resume their initial normal shapes and volumes when the application of compression and pulling forces is released, while these initial normal shapes and volumes can be retained indefinitely, through the action of heat if thermosetting plastic materials are used.

More particularly, one object of this invention is to provide a novel method of mounting rocking latch or clasp members for pivotal motion on self-acting needles of the type used for knitting and relooping works, this method being characterized by the fact that the pin bores of the latch member and side portions of the needle body are given smaller diameter and larger diameters respectively, than the normal outer diameter of the latch pivot pin, or conversely, larger diameter and smaller diameters respectively, than this said normal outer diameter, and that, in combination, this pivot pin for pivotally mounting the latch member between the side portions of the needle body consists of a cylindrical stub of synthetic plastic material adapted to be deformed momentarily, during the assembling of the parts, under the influence of various compression, pulling and/or torsional forces, before resuming its initial normal shape and volume.

Preferably, the synthetic plastic material used for

2

forming this cylindrical stub to be used as a latch pin in self-acting needles for knitting and relooping machines will be selected in the superpolyamide group and consists, more preferably, of a synthetic resin known and sold under the trade name of "Nylon."

In order better to understand the method according to the invention and how same may be carried out practically, the accompanying drawing illustrates diagrammatically some embodiments of the invention given solely by way of example. In the drawing:

Fig. 1 is an elevational side view of a latch-needle for knitting machines, of known type, illustrating the kind of needles to which the present invention is applicable, and wherein 1 is the body or stem of the needle terminating in a hook portion 2, and 3 the rocking latch mounted for pivotal motion about its metal pin 4.

Fig. 2 is a cross-sectional view along the pivot axis, according to a first embodiment of the invention;

Fig. 3 is a similar view of a second embodiment, and

Fig. 4 is another similar view of a modified embodiment.

Referring to Figs. 2, 3 and 4 of the drawing, which illustrate, at a much enlarged scale considering the slenderness of latch-needles, the three different embodiments of the invention, 1a, 1a are the two side portions which define the slit or groove 5 formed in the needle body 1 and between which the latch proper 3 is mounted for pivotal motion about its pin 4, consisting, according to the invention, of a cylindrical stub of "Nylon" thread, the initial normal diameter of which is designated by the reference letter a.

6 is the pin bore formed in the latch and 7, 7 those formed through the side portions 1a, 1a to receive the ends of the pivot pin 4.

Now regarding the first embodiment illustrated in Fig. 2, it will be noted that in view of the pivotal mounting of the pin, the bore 6 in latch member 3 has a somewhat smaller diameter than the initial normal diameter a of stub 4, while the diameter of bores 7, 7 in side portions 1a, 1a of the needle body is somewhat larger than the initial normal diameter a of this stub.

Thus, the method of assembling consists in placing the latch 3 in slit 5 with the pin bore 6 in alignment with the bores 7, 7 of side portions 1a, 1a; and, after having sharpened or pointed the end of a "Nylon" thread having an initial normal diameter a slightly greater than the pin bore 6, in threading this "Nylon" thread, first, freely through one of the bores 7, 7 of the side portions of the needle body 1; and then, in gradually pushing and twisting said thread through the pin bore 6 of the latch, until the pointed end of said thread comes out freely from the bore 7 of the other side portion of the needle.

With such a forced threading, the thread will be deformed and elongated while progressing through the parts and then, said thread is cut to length, i. e. flush with the outer faces of the needle side portions by means of a sharp blade or other suitable device.

As the "Nylon" thread has a tendency to resume its initial normal volume, the stub portion thereof which is placed in the latch pin bore 6 will be tightly clamped while the end portions of the pin will resume freely their initial normal diameter a while, at the same time, retracting themselves inside bores 7, 7 of side portion 1a, 1a in which they are journaled, thus avoiding any risk of catching the threads being knitted.

If desired and for additional safety, a further step may be carried out to prevent the pin ends from projecting from the needle side faces by lightly driving-in these ends with the assistance of a punch heated at a suitable temperature.

Referring now to the second embodiment illustrated in Fig. 3, it will be noted that in view of pivotally

mounting the latch, the diameter of its pin bore 6 is made somewhat larger than the initial normal diameter a of stub 4, while the diameter of bores 7, 7 in side portions 1a, 1a, is made slightly smaller than the initial normal diameter of said stub.

Thus, this method of assembling, which is much similar to the first embodiment described in connection with Fig. 2, consists in threading freely the pointed end of the nylon thread into the bore 7 of one of the needle side portions, then, force the thread by pushing and twisting it through this bore 7 and in so continuing moving the thread gradually and successively through said bore, until the pointed end which has freely passed through the latch bore 6, will emerge from the other side face of the needle through the corresponding bore 7 from which it will then be pulled in combination with the pushing action still exerted on the thread on the other or first side.

With this forced threading performed through combined extrusion and drawing of the thread, this latter will be deformed and elongated, the last step consisting, as in the first embodiment, in cutting the thread flush with both side faces of the latch-needle to form the pin or stub.

As it tends to resume its initial volume, the stub portion located inside the latch bore 6 comprised between the side portions 1a, 1a of the needle will expand to its initial normal diameter a , while the pin ends are tightly held in bores 7, 7 with their outer faces retracted inside these bores, whereby any catching of the knitted threads during operation of the needle is substantially prevented.

Referring now to the modified embodiment illustrated in Fig. 4, it will be seen that in view of the pivotal mounting of latch 3 in the needle, the diameter of the latch bore 6 is also slightly larger than the initial normal diameter a of stub 4, while the diameter of bores, 7, 7 in side portions 1a, 1a are substantially the same as the initial normal diameter a of stub 4, said bores being countersunk at 7a, 7a.

Under these conditions, the assembling is simplified as it simply consists in engaging successively the "Nylon" thread through bores 7, 6, 7, almost without forcing it, then cutting said thread flush with the outer faces of the needle, and finally driving the ends of the thus formed pin into the bores by means of a heated punch so as to form these ends with countersunk heads 4a, whereby pin 4 will be safely held against axial motion and prevented from catching the threads when the needle is in operation.

This method of mounting the latch for pivotal motion in latch-needles avoids the drawbacks resulting from conventional metal pin assemblies and is also advantageous in that worn or otherwise spoiled latches may be readily replaced by driving out the pins from the assembly, by simply using a chasing point.

While I have shown and described some embodiments in which my invention may be carried out, it will be understood that various details may be altered without departing from the spirit and scope thereof. Furthermore, I do not wish to be construed as limiting my invention to the specific embodiments illustrated, except as it may be limited in the appended claim.

I claim:

15 A method of mounting a latch or clasp member for pivotal motion on a self-acting needle for knitting and relooping, said method comprising forming a pin-bore in a latch member, forming a latch-receiving groove in a needle body, whereby said portions are formed in the needle body on opposite sides of said groove, forming a pair of aligned pin-bores in said side portions, said latch pin-bores having a diameter which is different from the diameter of said pair of side pin-bores, placing said latch member in said groove with the latch pin-bore in axial alignment with said pair of side pin-bores, forcing a pin of synthetic plastic material of the superpolyamide group the initial normal diameter of which is smaller than the largest diameter of said bores and larger than the smallest diameter of said bores, through said bores while 20 subjecting said pin to axial compression and deforming it momentarily until the pin is positioned beyond said bores, cutting said pin flush with both outer faces of said side portions, and allowing a portion of the pin to resume its initial normal diameter while the end portions 25 of the pin are retracted into said side pin-bores, whereby said latch member will be journaled for free pivotal motion.
